UNITED STATES PATENT OFFICE.

JOHN R. MACKINNON, OF BOSTON, MASSACHUSETTS.

SALIVA EJECTOR.

Application filed April 22, 1925. Serial No. 25,052.

My invention relates to saliva ejectors and will be best understood from the following description when read in light of the accompanying drawings showing one specific embodiment of my invention, while the scope of my invention will be more particularly pointed out in the appended claims.

In the drawings:

Fig. 1 is an elevation of the assembled 10 ejector;

Fig. 2 is an elevation on an enlarged scale of the end of the ejector, parts being shown in section; and

Figs. 3 and 4 are respectively a side and 15 front elevation on an enlarged scale of the tube forming the body of the ejector.

Referring to the drawings and to the preferred embodiment of my invention I have shown an ejector which comprises a tube 1 bent as is indicated at 3 for giving it a 20 shape convenient for use in connection with dental or oral operations, the tube being conveniently attached to a suitable hose 5 leading to an aspirator or other means of creating suction.

Referring particularly to Figs. 2, 3 and 4 I have shown the end of the tube formed with lateral substantially V-shaped notches 7, a portion of the tube being continued beyond 30 the end of the body of the tube and bent across the end of the tube as is indicated at 9.

For providing a guard to prevent the tissue of the mouth from clogging the end 35 of the tube, and for purposes which will hereinafter be explained, I provide a guard in the form of a cap 11 having cylindrical walls surrounding the tube and spaced therefrom to form a chamber 13 and having an 40 imperforate end wall 15 which is secured to the portion 9 of the tube, preferably by soldering as is indicated at 17.

That end of the guard or cap 11 opposite the end 15 is beveled as is indicated at 19 so as to make the cylindrical walls of the cap at one side of the tube 21 of greater 45 length than those at the opposite side 23 of the tube.

In practice the ejector is placed in the 50 mouth of the patient and the saliva rises until it passes over the side 23 of the tube, when it is drawn into the chamber 13 and enters the tube through the openings 7 by reason of the suction. At the same time

the air entering the chamber 13 is drawn 55 into the tube and effectively acts to remove the saliva.

I have found that where the cylindrical walls of the cap are of uniform height the tendency of the ejector is to choke, and that 60 by constructing the cap with the beveled portion 19 so as to form in substance when the device is in operation a saliva entry port 25 and an air entry port 27, the former being closer to the end of the tube than the latter, a much more effective removal of the 65 saliva and more satisfactory operation of the device is secured.

The use of saliva ejectors as heretofore constructed has been accomplished only with 70 severe discomfort to the patient in cases where the tissue of the mouth or tongue would clog the suction orifices of the ejector. With an ejector constructed according to the example of my invention disclosed in the 75 application drawing the edge 23 of the cap when the ejector is inserted commonly will be buried in the soft tissue on the floor of the mouth, while the tongue will rest, if at all, against the high side of the cap. The 80 beveled edge 19 of the cap provides that air will always enter the cap even if the tissue should clog the cap at the low point 23 and the tongue should clog the cap at the high point 21. Foreign matter, for example particles of filling, absorbent cotton, etc., may 85 enter the cap with the saliva and tend to clog the opening or openings 7, but as the upper portions of the slots 7 are above the low point 23 of the cap and consequently 90 above the saliva the upper portions of the slots 7 cannot be clogged, and therefore always permit entrance of air to the tube. In other words, the submitted embodiment of 95 my invention by providing substantially two suction openings, herein by having one side of the cap higher than the other and having the tops of the slots 7 above the low point 23 of the cap, prevents full application of the suction to the tissue if the latter should enter 100 the cap and therefore is less painful to the patient in cases where the tissue does enter the cap at the low point 23.

Although I have described for purposes of 105 illustration one specific embodiment of my invention it is to be understood that I am not limited thereby to the particular mechanical details, but that within the scope of my in-

vention wide deviations may be made therefrom without departing from the spirit of my invention.

1. An ejector for saliva or the like comprising a tube the end portion of which is formed to provide a lateral opening and an integral cap securing member forwardly of said opening, a cap secured to said cap securing member, said cap having an imperforate end wall forwardly of said lateral opening and a cylindrical wall spaced from and surrounding the end of said tube, the end of the cylindrical wall of said cap opposite said end wall being substantially beveled to provide for said cap when the ejector is in operation an air entry port and a saliva entry port, said saliva entry port being between said air entry port and the end wall of said cap.
- 10 2. An ejector for saliva or the like comprising a tube the end portion of which is formed to provide a lateral opening, a cap over the end of said tube, said cap having an imperforate end wall forwardly of said lateral opening and cylindrical walls spaced from and surrounding said tube, said cylindrical walls of said cap extending for a greater distance from the end wall of said cap at one side of said tube than at the opposite side of said tube, and said lateral opening extending from the end of the cap a greater distance than the cylindrical walls of the cap at the last mentioned side of the tube.
- 15 3. An ejector for saliva or the like comprising a tube the end portion of which is formed to provide a lateral opening, a cap over the end of said tube, said cap having a closed end forwardly of said lateral opening and having a lateral wall spaced from the

wall of said tube, and the lateral wall of said cap extending from the closed end of said cap for a greater distance at one portion thereof than at another portion thereof and said lateral opening extending from the end of the cap a greater distance than the cylindrical walls of the cap at the last mentioned side of the tube. 45

4. An ejector for saliva or the like comprising a tube, a cap over the end of said tube, said cap having a closed end and having lateral walls surrounding said tube and providing a chamber between said tube and said lateral walls, the interior of said cap being in fluid communication with said tube 50 rearwardly of the closed end of said cap, means forming when said ejector is in operation a saliva port and an air port to said chamber, said saliva port being spaced lengthwise of said tube from said air port 60 and situated nearer the closed end of said cap than said air port, and means providing communication between the interiors of said cap and tube intermediate said saliva and air ports in the direction of the length of said tube and intermediate said saliva port and the closed end of said cap. 65

5. A saliva ejector comprising a tube having lateral end opening, a cap over the end of said tube, said cap having a closed end and lateral walls, said lateral walls having the beveled portion 19 for providing when said ejector is in operation the ports 25 and 27, spaced lengthwise of said tube, said lateral end opening extending lengthwise of 70 the tube from one side of said port 25 to the other. 75

In testimony whereof, I have signed my name to this specification.

JOHN R. MACKINNON.
